UNITED STATES PATENT OFFICE.

OLIVER C. CURTISS, OF PHILADELPHIA, PENNSYLVANIA.

TOY SAVINGS BANK.

Application filed July 26, 1920. Serial No. 398,889.

To all whom it may concern:

Be it known that I, OLIVER C. CURTISS, a citizen of the United States, residing at Philadelphia, in the county of Philadelphia and State of Pennsylvania, have invented 5 certain new and useful Improvements in Toy Savings Banks, of which the following is a specification.

The main object of my present invention 10 is to make a toy savings bank which will have the appearance of a miniature cabinet talking machine and as such will attract so much attention and inspection that it will be an incentive for a child or other person 15 to deposit money therein.

Another object is to so construct my improved bank that it will have certain parts which are movable in the same manner as parts of an actual cabinet type of talking 20 machine such for example as a hinged lid and front doors, and to so arrange the doors that when closed they will cover the coin slot.

Another object is to so construct and arrange the parts that they may be made of 25 cardboard, glass, metal or other suitable material.

These objects, and other advantageous ends 30 which will be described hereinafter, I attain in the following manner, reference being had to the accompanying drawings in which—

Figure 1 is a face view of a cardboard blank which is cut, scored and printed so 35 that when folded and pasted it will form a bank of the above described character,

Figure 2 is a perspective view showing the blank of Figure 1 partly folded,

Figure 3 is a perspective view showing 40 said blank after it has been pasted together and finished with the exception of a removable top portion which I preferably employ.

Figure 4 is a perspective view of the completed bank,

Figure 5 is a sectional elevation taken 45 centrally through the front and rear of the bank,

Figure 6 is a side elevation of a removable cap which fits in a hole in the top of the 50 bank and which has the appearance of a record and turntable when placed in position as shown in Figures 4 and 5.

Figure 7 is an inverted plan view of the cap of Figure 6,

Figure 8 is a sectional elevation taken on 55 the line 8—8 of Figure 7,

Figure 9 shows a developed paper blank which may be cut, scored and printed and used as an outside covering or facing such for example as could be used on the blank 60 of Figure 1 after it has been folded and pasted if it is not desired to directly print the various talking machine features on the cardboard blank,

Figure 10 is a front elevation showing a 65 bank made in accordance with my invention such for example as a bank which is made of folded or cast metal, molded or blown glass, or other suitable material,

Figure 11 is a side elevation of Figure 10 70 with the lid open,

Figure 12 is a transverse sectional elevation of Figure 10, and

Figure 13 is a sectional elevation taken 75 on the line 13—13 of Figure 10 with the doors closed.

Referring to the drawings and particularly to Figures 1 to 8 inclusive a single blank 14 which may be of cardboard is cut or stamped in the shape illustrated in Figure 1 and includes a back portion 15, two side portions 16 and 17 extending from the back portion, a lid portion 18, a bottom portion 19, front portion 20 and a top portion 21. The above mentioned portions are all 80 formed integral; the side portions 16 and 17 being adapted to be bent upon scored lines 22 and 23. The lid portion 18 may be bent on the scored line 24 and the bottom portion 19 may be bent on the scored lines 90 25 and 26; the blank being cut at 27 to provide rear legs 28; the scoring lines 22 and 23 extending downwardly through the portions which form the rear legs so that when folded the rear legs will be angular in cross 95 section; a part being in the plane of the back portion while other parts are in planes with the sides 16 and 17. The front legs 29 project part way from the outer edges 30 and 31 of the sides 16 and 17 and include a 100 scored line 32. The scored line 25 is substantially on the level of the bottom edges 33 of the sides 16 and 17 so that when the bottom is folded as clearly shown in Figures 2 and 5, the bottom 19 will form a 105 snug fit between the front, back and side portions. The lid 18 has notches 34 cut out of its corners and includes scored lines 35

to permit the edge portions of the lid to be bent to provide a hollow lid with bevels adjacent its edges as clearly shown in Figures 3, 4 and 5. The parts adjacent the notches 5 may be pasted together or if desired the interior or exterior surface may be covered with a sheet of paper to hold the edge portions in their beveled arrangement. The front portion 20 includes an upper part 36 10 which has transversely scored lines 37, 38 and 39. A coin slot 40 is cut out of the part 36 preferably in alignment with the scored line 38 and the part 36 is bent on the lines 37, 38 and 39 to provide an indentation 41 15 which is adapted, when the parts are folded as shown in Figures 2 and 3, to include the coin slot 40 at its innermost part. The top portion 21 preferably includes a scored flap 42 which may be coated with adhesive material and adapted to be pasted against the inner surface of the back portion 15 with the upper surface 43 of the top portion at the level of the top edges 44 of the side portions 16 and 17. The top portion 21 includes a hole 45 25 designed to receive the depending flange or collar 46 of a removable cap 47; said cap having a head 48 in the form of a disk which may be printed and colored to represent a turntable of a talking machine with a record thereon. If desired a small pin 49 may be inserted upwardly through the head 48 to represent the centering pin of a talking machine turntable as clearly shown in Figures 5, 6, 7 and 8. The top portion 21 is also preferably provided 30 with side scored flaps 50 which may be coated with adhesive material and the front section 20 is also preferably provided with side flaps 51 which are scored and coated 35 with adhesive material and these side flaps of the top and front portions can be pasted against the inner surfaces of the sides 16 and 17 when the latter are folded into position. In similar manner the bottom section 40 45 19 is preferably provided with side flaps 52 which are scored and coated with adhesive material and arranged to be pasted against the inner surfaces of said sides 16 and 17. The sides 16 and 17 have laterally scored 50 55 extensions 53 arranged at a position to represent doors and are adapted to swing on their scorings 54 as hinges to cover the indentations 41 including the coin slot 40. The front legs 29 have a transverse scoring 55 60 55 and are cut downwardly in the plane of the edges 30 and 31 as shown at 56 to provide angular tabs 57 which are preferably coated with adhesive material so that when the front legs are bent on the scorings 32 65 and the parts are pasted together the tabs 57 will engage the inner surface of the part between the scorings 25^a and 26^a adjacent the bottom 19 as shown in Figure 5.

Various features of a talking machine 65 may be printed or otherwise formed on the

outer surfaces of different portions of the blank so that when the blank is folded and pasted together, said features will occupy positions which they occupy on a talking machine cabinet. For example the side 16 70 has the representation of a winding hand crank 58 printed or otherwise formed thereon. The front portion 20 has the representation of cabinet doors 59 formed thereon. The top portion 21 together with the disk 75 head 48 has the representation of a tone arm 60 printed or otherwise formed thereon. In similar manner other representations, such for example as key holes, door knobs and other well known parts of a cabinet talking machine, may be printed or otherwise produced. 80

Coins can be inserted into the hollow body portion of the bank through the coin slot 40 and if desired to remove the money the cap 47 can be lifted out of the hole 45 after the lid has been raised. The cardboard may be colored to represent various kinds of wood such for example as mahogany, oak or the like and if it is desired to use a plain cardboard without any representations thereon the parts can be folded and secured together as above described and a paper blank used to cover the cardboard, such for example as the paper blank shown in Figure 9. This 95 paper blank may be colored and printed to include the representative parts as above specifically described and in this manner a complete covering for the visible portions may be had. The inner surface of the paper 100 blank shown in Figure 9 may be coated with adhesive material and quickly pasted so as to cover all of the visible parts and in some instances may be preferred to the method of construction above described where the cardboard blank has the representative features of the talking machine directly printed or otherwise formed thereon. 105

In Figures 10 to 13 inclusive I have shown a construction in which my improved 110 bank may be made by casting or molding the same out of metal or by making the parts out of glass and in this form the doors 53^a may be connected by hinges 54^a to the hollow body portion to cover the indentation 115 41^a which includes the coin slot 40^a. The lid 18^a may be connected to the hollow body portion by hinges 24^a and if desired the interior of the hole 45^a may be screw threaded to receive the screw threaded collar 46^a of a cap 47^a. The outer surfaces 120 of the various portions may be painted or otherwise colored and the various representative features of a talking machine can be provided in the same manner as above described. 125

While I have described my invention as taking particular forms, it will be understood that the various parts of my invention may be changed without departing from the 130

spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. A toy savings bank constructed from a blank composed of a longitudinal series of flexibly bent members and two laterally extending members, said members being bent and joined at their meeting edges to form the top, front, bottom, back, sides and lid of an imitation talking machine.

2. A toy savings bank constructed from a blank composed of a longitudinal series of flexibly bent members and two laterally extending members, said members being bent and joined at their meeting edges to form the top, front, bottom, back and sides of an imitation talking machine, the lateral members having extensions forming legs.

3. A toy savings bank constructed from a blank composed of a longitudinal series of flexibly bent members and two laterally extending members, said members being bent and joined at their meeting edges to form the top, front, bottom, back and sides of an imitation talking machine; the top having an annular opening and a removable cap having a disk shaped head mounted in the opening.

4. A toy savings bank constructed from a blank composed of a longitudinal series of flexibly bent members and two laterally extending members, said members being bent and joined at their meeting edges to form the top, front, bottom, back and sides of an imitation talking machine; a part of

the front member of the blank being bent to form an inwardly extending bellows fold and provided with a coin slot in the inner edge of a fold.

5. A toy savings bank constructed from a blank composed of a longitudinal series of flexibly bent members and two laterally extending members, said members being bent and joined at their meeting edges to form the top, front, bottom, back and sides of an imitation talking machine; a part of the front member of the blank being bent to form an inwardly extending bellows fold and provided with a coin slot in the inner edge of a fold; the side members having extensions forming doors adapted to close over the fold.

6. A toy savings bank including a body consisting of bottom, side, front, rear and top walls, the top wall having an opening, a removable cap adapted to close the opening and a lid adapted to close over the top.

7. A toy savings bank including a body consisting of bottom, side, front, rear and top walls, one of the walls having an inwardly extending bellows fold provided with a coin slot.

8. A toy savings bank including a body consisting of bottom, side, front, rear and top walls, one of the walls having an inwardly extending bellows fold, provided with a coin slot, and doors adapted to close over the bellows fold.

In testimony whereof I have signed my name to this specification in the presence of two subscribing witnesses.

OLIVER C. CURTISS.
